UNITED STATES PATENT OFFICE.

JULES ALBERT AGERON AND BLAISE JEAN MARIE REMY, OF LYON, FRANCE.

EXPLOSION-MOTOR-STARTING MECHANISM.

No. 853,615.

Specification of Letters Patent.

Patented May 14, 1907.

Application filed July 23, 1906. Serial No. 327,381.

To all whom it may concern:

Be it known that we, JULES ALBERT AGERON and BLAISE JEAN MARIE REMY, citizens of the French Republic, residing at Lyon, France, have invented certain new and useful Improvements in Explosion-Motor-Starting Mechanism, of which the following is a specification.

This invention relates to explosion motor starting mechanism in which the motive force necessary for overcoming the resistance of the explosion motor to the rotation of its crank shaft previously to the occurrence of an explosion therein, is derived from a fluid under pressure.

The improved starting mechanism is illustrated in the annexed drawing in which:

Figure 1 is a section on line A—A of Fig. 2 and Fig. 2 is a plan partly in section showing part of the frame of a motor or of a motor car and of the motor starting shaft with the improved starting mechanism applied thereto. Fig. 3 is a front elevation and Fig. 4 a horizontal section on line B B of Fig. 3 illustrating another form of the improved starting mechanism.

In Figs. 1 and 2 *a* may represent the front transverse member of a motor car frame, or any member transverse to the axis of the motor. *n* represents the starting shaft of the motor which engages the crank shaft of the latter. To the shaft *n* is connected the screw threaded spindle *k* by means of ratchet gear of any known kind *k'* permitting of the spindle *k* revolving in one direction independently of the shaft *n* but causing the rotation of the spindle *k* in the other direction to rotate also the shaft *n*. The threads of the spindle *k* are of steep pitch. The spindle *k* is journaled in the plate *m* bolted to member *a* and in the bracket *l*. On the plate *m* are fixed two trunk pistons *b b*, on which slide two cylinders *c c* connected together by a bridge *c'* in which is cavity *c''* in which the nut *i* is journaled. This nut *i* engages the spindle *k*. The nut *i* is normally held from revolution in the bridge *c'* by a set screw *j*. *f* is a socket to which is connected a pipe from a suitable reservoir of compressed elastic fluid. *e e* are passageways from socket *f* to the outer ends of pistons *b b*. Other passageways *g g* extend from the ends of pistons *b b* to ports *h h* in the sides of said pistons. A spring *o* is interposed between the nut *i* and the end of the bracket *l*.

When elastic fluid is admitted from the

reservoir to the passages *e e* it expands in the cylinders *c c* and forces them outward from the pistons *b b*. The bridge *c'* connecting the pistons, and the nut *i* thus move outward and the nut, being prevented from turning causes the spindle *k* to be turned, and the spindle turns the starting shaft *n*. At the end of the outstroke of the cylinders *c c* the ports *h h* are uncovered and the elastic fluid escapes, the spring *o* will then return the parts to their previous position, it being understood that the inlet of motive fluid to passages *e e* has been cut off.

In the form of construction shown in Figs. 3 and 4 a single cylinder *6* is axially concentric with the spindle *1*. The cylinder *6* is formed with a sleeve *18* passing through the frame member *10* and forming a stuffing box fitted with a gland *11* through which passes a cylindrical journal *9* on the spindle *1*. The piston *4* is formed with a sleeve *5* cylindrical interiorly to receive the spindle *1* and prismatic exteriorly to move longitudinally without revolution in a prismatic guide *14* forming part of the head *7* of the cylinder *6*. The head *7* is not integral with the cylinder *6* but is made to be capable of revolving independently. It is however normally held stationary either by the frictional force of the screw cap *8* or by a spring locking dog *17*. The outer end of sleeve *5* is closed by a screw plug with squared head *15*. The piston *4* is also made to receive the non-rotary nut *2* engaging the threads on the spindle *1*. At the inner end of the spindle *1* is a squared end *3* to engage the motor starting shaft. Within the cylinder *6* is a spring *12* bearing on the piston *4*. *13* represents the port for inlet or outlet of elastic pressure fluid.

When the pressure fluid is admitted the piston *4* is driven back against the pressure of spring *12*. It cannot revolve owing to the prismatic sleeve *5* and the fixed head *7*. The nut *2* therefore revolves the spindle *1*.

Should the apparatus fail to operate by reason of exhaustion of motive fluid or otherwise the spindle *1* or *l* may be revolved independently by hand after the means which prevent the nut *i* or *2* from revolving has been put out of action, that is to say by loosening the set screw *j* (Fig. 1) or the cylinder head *7* (Fig. 4).

What we claim as our invention and desire to secure by Letters Patent of the United States is:

1. In a motor starting device the combina-

tion with a motor starting shaft, of a steep pitch screw threaded spindle, connections between said shaft and spindle, a nut engaging the spindle and a piston pressure device operative to propel the nut longitudinally of the spindle together with detachable means for preventing said nut from revolving.

2. In a motor starting device the combination with a motor starting shaft, of a steep pitch screw threaded spindle, connections between said shaft and spindle, a nut engaging the spindle and a piston pressure device

operative to propel the nut longitudinally of the spindle together with detachable means for preventing said nut from revolving and a spring operative to return said nut to its normal resting position. 15

In witness whereof we have signed this specification in the presence of two witnesses.

JULES ALBERT AGERON.

BLAISE JEAN MARIE REMY.
